(57) **CLAIM**

The ornamental design for a tire for automobile, as shown and described.

DESCRIPTION

FIG. 1 is a left perspective view of a tire for automobile showing my new design;

FIG. 2 is a front view thereof;

FIG. 3 is a rear view thereof;

FIG. 4 is a left side view thereof; and,

FIG. 5 is a partial enlarged view of FIG. 2.

The top view and the bottom view are the same as the front view. The right side view is the same as the left side view.
